UNITED STATES PATENT OFFICE.

JAMES WHITELAW, OF ST. LOUIS, MISSOURI.

SEWING-MACHINE FOR BLINDSTITCHING.

1,195,633.

Specification of Letters Patent. Patented Aug. 22, 1916.

Application filed January 8, 1912. Serial No. 669,927.

To all whom it may concern:

Be it known that I, JAMES WHITELAW, a citizen of the United States, residing at St. Louis, in the State of Missouri, have invented certain new and useful Improvements in Sewing-Machines for Blindstitching, of which the following is a specification.

My invention relates to improvements in sewing machines for blind stitching, and has for its general object to provide a simple, efficient, compact, and robust machine, particularly adapted, in some of its features, for making a blind chain-stitch.

In the drawings, wherein I have illustrated an embodiment of my invention, Figure 1 is a front elevation thereof with the cover plate removed and parts broken away; Fig. 2 is a similar plan view; Fig. 3 is an enlarged perspective detail showing the stitch-forming mechanism in operation; Fig. 4 is an end elevation from the stitching end (left of Fig. 1); Fig. 5 is a section on line 5—5 of Fig. 1; Fig. 6 is a section on line 6—6 of Fig. 1; Fig. 7 is a section on line 7—7 of Fig. 1; Fig. 8 is a horizontal section on line 8—8 of Fig. 1; Fig. 9 is a plan detail of the feed plate and contiguous parts; Fig. 10 is a longitudinal section on line 10—10 of Fig. 4; Fig. 11 is a transverse section on line 11—11 of Fig. 1; Fig. 12 is a section on line 12—12 of Fig. 1; Fig. 13 is a section on line 13—13 of Fig. 11; Fig. 14 is a detail of an eccentric construction on the back of the frame; Figs. 15, 16, and 17 are perspective details showing successive phases in the stitch formation; Fig. 18 shows the stitch formation; and, Fig. 19 is a cross section on line 19—19 of Fig. 2.

In the specific construction shown in the drawings, the main frame 25 is provided at one end with a base 26 from which rises an end wall 27 and a rear wall 28, the latter branching longitudinally into the rear walls 29 and 30, respectively, of two longitudinal arms which are to afford support respectively for the stitch-forming mechanism and the work-handling mechanism. Integral with the arms 29 and 30 is a continuing transverse wall 31 having an upper portion 32 forming the bottom wall of the upper arm and an opposed portion 33 forming the top of the lower arm. With this integral frame structure may be associated a single piece detachable cover member 34, providing a front wall suitably shaped to coöperate

with the walls 33 and 32 of the respective arms, and with a top wall shaped to coact with the upper surface of the arm 29, thereby to house the gear mechanism, shafting, and the like, contained in the right end of the machine. The cover piece 34 may conveniently be secured in place by a single thumb screw 35, taking into a suitably shaped edge portion of the cover member and engaging in a slot 36 in the rear wall 28 of the main frame member.

The driving shaft 40 of the machine extends transversely through an elongated bearing sleeve 41, preferably provided with an oil recess 42 and mounted in a suitable boss 43 in the rear wall 28 of the frame, said shaft at its outer end bearing the pulley-hand-wheel 44 and an eccentric 45, and inside of the frame bearing a disk 46 which may conveniently be made in shape to perform the work of several elements.

The eccentric 45, through the strap 47 and arm 48, moves the crank 49 on a needle bar shaft 50 which extends through a suitable transverse bearing at the end or head of upper arm 29, and said shaft bears the needle bar 51, in which is mounted the needle 52. The needle, which is preferably of curved, side-pointed construction, slightly angulated to the path of its reciprocation, is secured in the arm by a clamp member 53 having an extension wing 54 in which there are made a thread eye 55 and groove 56, the latter being overlain near its lower end by the tip of an L-shaped spring 57, as best shown in Fig. 4.

The needle works over the top of a presser-foot 60 vertically guided in and secured to a head end of upper arm 29, as by screw 61'. The stationary presser-foot 60 has its under side suitably shaped for coaction with the cloth-handling devices and is provided with a central aperture 61 through which a portion of the cloth to be stitched may be presented to the needle. To the top of the presser foot is attached a needle-deflecting guide 62, to steady and deflect the needle adjacent its point of penetration of the goods, and in said presser-foot is made a clearance recess 63 for a looper point to be described.

The looper 70 is a vertical member, preferably provided with a single horizontal point 71 at its lower end, its shank at its upper end adjustably engaging an enlargement 72 of a horizontal looper bar 73, the

looper 70 being retained in adjusted position by a set screw 74, taking through the enlargement 72. The looper bar 73 is mounted with respect to the frame so that its active 5 end, *i. e.*, that carrying the looper 70, may be vertically displaced, reciprocated longitudinally and oscillated transversely. Thus the rear end of bar 73 slides in a T-shaped bearing head 76 the stem of which is mounted to 10 turn in a bearing 77 projecting from the rear wall of the frame. Near its forward end the bar 73 passes through a guide block 78 in which it may turn, but with respect to which it is longitudinally fixed against 15 movement by a shoulder 79 on the bar in front of the block 78 and a sleeve 80 secured by a pin 81 to said bar in rear of the block. The guide block 78 is carried by transverse pivot pins 83 and 84 in a swinging yoke 85, which in turn is carried by a transverse 20 pivot 86 extending through a sleeve 87 and secured therein as by collar 88, said sleeve 87 having a screw-threaded portion engaging a threaded slot 89 in the frame wall 29 25 to be secured at the desired elevation by a lock nut 90. Manifestly as the yoke 85 stands above its pivotal axis, and is oscillated through an arc crossing a line drawn vertically through its pivotal axis it will 30 raise and lower the active end of the looper bar 73 vertically, and will carry the looper bar bodily in a longitudinal or axial direction, both such movements being permitted by the sliding mounting of the bar in the 35 bearing 76 and the pivotal mounting of the said bearing 76 and the block 78. Such oscillating movement is imparted to the yoke 85 by a link 91 which extends from a wrist pin 92 on the yoke to a wrist pin 93 40 on the disk 46, heretofore mentioned. An oscillating movement about its own axis is also imparted to the looper bar 73 and to this end sleeve 80 is provided with a pendent arm 95, carrying a rod 96 paralleling 45 looper bar 73, said rod 96 engaging a vertically slotted yoke 97 carried by a longitudinally extending arm 98 of a bell crank lever 99 mounted on the vertical stud 100 projecting from the wall 32 of the frame, said 50 bell crank lever having a lateral arm 101 to which is connected a link 102 the opposite extremity whereof is pivoted to a nose 103 of a pendent link 104, said link being pivoted as at 105 to the frame and bearing 55 a roller 107 actuated by a suitable cam on the main shaft. To provide such cam I preferably provide a cam groove 108 in the disk 46, as best shown in Figs. 11 and 13. Manifestly through the connections described, the cam 108 on the main shaft causes 60 looper bar 73 to oscillate about its own axis, thereby to shift the point of the looper transversely with reference to the path of reciprocation of the needle. In practice, the cam is so shaped and the timing of the parts

is such that as the needle is in its most retracted position, substantially as shown in Fig. 3, the looper point is descending into the recess 63 (to spread a loop previously taken) and in such position it dwells (owing 70 to the shape of the cam 108 and the fact that wrist pin 93 is passing dead center) until the needle passes close behind the looper (to enter the spread loop) (see Fig. 15). Thereupon the looper is raised vertically by the oscillation of the yoke 85 75 toward vertical position and, after it clears the needle, said looper is moved laterally toward the back of the machine by the operation of the cam (see Fig. 16), the looper 80 point being thence carried in an ovate curve downward and toward the right to pass just over the needle (and take the new loop) as the needle is being retracted (see Figs. 16 and 17). 85

To prevent the loop of the needle thread from sagging or falling laterally to such position that it may be missed by the looper point, I may provide upon the presser foot, just out of the looper path, two small pins 90 on opposite sides of the path of the needle, preferably connected across the top to constitute a yoke 110.

Thread A is fed from any suitable source of supply through a suitable tension 95 111 and thread eyes 112 and 113 to a take-up arm 114, and thence to the eye 55 of the needle-holding plate, down in groove 56 under spring 57 to the needle-groove and eye. 100

In order that the take-up may advantageously be actuated and timed by the looper mechanism and may be caused to make a relatively long and rapid take-up excursion immediately after the needle engages the preceding loop, may make a long dwell during the time that the looper is taking the loop from the needle, and may rapidly move to give thread while the looper is carrying the loop, I provide a construction as follows: The take-up arm 114 and a second arm 115 are pivoted, side by side on a stud 116, said stud being carried by a radius arm 117 projecting vertically from the stem 118, said stem 118 being rotatably adjustable in a suitable bearing in the frame, and secured by a set screw 119. The arm 115 is connected by a link 121 with the pivot member 83 carried by yoke 85, so that it oscillates in harmony with said yoke. The 110 take-up arm 114 normally abuts against the end of the link 121 for movement therewith, and is held in such position by a spring 123 extending between pin 124 on the arm 115 and a finger 125 on the take-up arm. The 120 take-up arm is, however, provided with another finger 126 rearwardly bent, as shown in Fig. 4, so that at a predetermined point about midway in the excursion of the arm 115 said finger 126 strikes the bearing mem- 130

ber 117, which acts as a stop therefor, and comes abruptly to rest practically as the yoke 85 passes vertical dead center. Thus in the cycle of operations of the machine, the 5 take-up dwells briefly (at the end of the outward movement) concurrently with the dwell of the looper, as the needle is taking the loop from the looper, and immediately thereafter the take-up begins its sweep 10 toward the right, rapidly taking up the thread until just about the time that the needle completes its penetrating thrust, whereupon the travel of the take-up is abruptly interrupted and the take-up then re- 15 mains at rest until after the looper has completed its loop-taking movement across the needle path, and then as the looper is in the course of its forward travel to loop-delivering position, such travel of the looper being 20 accompanied by a relatively rapid movement of the take-up in a thread-slacking direction.

The work handling mechanism, arranged below and coöperating with the stationary 25 presser foot 60 comprises a clamp member to hold the goods to the under side of the presser foot, a feed member for advancing the goods, and a plunger member for elevating a node of the goods to be acted upon 30 by the needle while the surrounding goods is clamped by the clamping member.

The clamp member 130 extending transversely of the machine, or away from the operator, is arched preferably in both the 35 direction of its length and of its width. It is carried by the finger 131 of a bell crank lever 132 fixed to a longitudinal shaft 133 which finds a bearing in a suitable projection of a block 134, said block supplementing the extremity of the lower arm casting 40 to provide the necessary bearings for parts to be described, and secured to said arm extremity as by a screw 135. The extremity of crank arm 132 has an enlargement 136 from 45 which extends an arm 137 connected to the mid-portion of the clamp member 130, and in the enlargement 136 is made a squared aperture engaging a squared portion 139 of a sleeve 140 in which rotates the extremity 50 of the feed actuating shaft 141. Said feed shaft is made in two sections 141^x and 141^a, the last named section being mounted in constant position in a sleeve 142 secured to the end wall 27 of the frame, and connected to 55 the forward portion 141^x by a universal joint, and said shaft section 141^a being driven by a spiral gear from the main shaft 40. Specifically disk 46 is provided with a spiral gear 146 cut on its periphery and 60 meshing (in one-to-one geared relation) with the spiral pinion 147 secured to the shaft section 141^a, said gear 147 having longitudinally projecting ears 148 in which is pivoted, as at 149, (Fig. 1), a block 150 65 (Fig. 8) having pivoted thereto on pin 151

at right angles to pivot 149 a yoke 152 connected with shaft section 141^x.

The clamp member 130 is preferably arranged to be elevated to clamping position by a friction-drive mechanism working on its shaft 133, and to this end the feed shaft section 141^a is provided, preferably beyond the frame wall 27 with a spur pinion 155 meshing with a gear 156 loosely mounted on the hub 157 of a disk 158 secured to the shaft 70 133, which extends the full length of the machine. The disk 158 is opposed by a second disk 159 lying on the opposite side of the gear 156 and slideable relative to the disk 158 on pins 160, the confronting faces of 75 the two disks 158 and 159 which coact with the gear 156 being faced with felt, or other appropriate material, as at 161. The disk 159 is pressed toward the disk 158 to exert a friction grip on the gear 156 by means of a 80 spring 162 surrounding the extremity of the shaft 133 abutting at one end against the disk 159 and at its outer end against a nut 162 on the threaded extremity of the shaft 133. The friction gear described may 85 conveniently be housed in an extension 164 forming a detachable extension of the end 90 wall of the casing.

When the driving pulley is rotated in a clock-wise direction (as indicated by the arrow in Fig. 1) the gear wheel 156 is rotated to move its top toward the operator and the friction disk carried by the shaft 133 tends to move therewith, so that the clamp member is raised to clamping position, but may be 95 depressed at any time against the resistance of the frictional elevating means. A stud 165 upon the disk 158 affords a point for connection of a lifting knee lever, not shown, by which the shaft 133 may be rocked to depress 100 the clamp whenever desired.

The feed member comprises a vertical feed dog 170 having its top shaped to provide two parallel feed points lying side by side and connected together at their front and 110 rear ends to leave an intervening space for the accommodation of the plunger to be described, the clamp member being provided with suitable openings 173 for the movement of the feed points 171, and with an intermediate opening 174 to accommodate the plunger. The lower end of the feed member is slotted as at 175 adjustably to receive a bolt 176 clamped to the dog by a nut 177, said bolt being mounted to rock with an arm 179 115 pivoted as at 180 to the front of the frame. The feed member is socketed to connect with a parti-spherical eccentric 181 secured to the feed shaft section 141^x, so that under the action of the eccentric it rises, carrying with 120 it the bolt 176, and falls, and oscillates fore and aft on said bolt 176 as a center. It will be apparent that if the feed dog be adjusted to meet the under side of the presser foot before it completes its rise, the action of the 125 130

eccentric will depress the shaft section 141* and carry down with it, through lever connection 132, the clamp plate 130, so to free the goods for advance by the feed. Depression of the clamp plate for insertion of goods carries with it the feed through the connection of arm 132 with the feed shaft.

The plunger proper 187, arranged to work through the appropriate openings in the feed, clamp, and presser foot, is carried by vertical slide 188 suitably guided in the frame for vertical reciprocation. Reciprocating motion is imparted thereto from a longitudinal rock shaft 190 through a lever 191 on said shaft, and a link 192 connecting said lever with the slide 188. The rear end of said plunger shaft is supported in suitable bearings 193 and is connected by crank arm 194 with the strap 195 of an eccentric 153 on the feed shaft. The front end of the plunger shaft 190 is mounted in a slide block 196 vertically guided in the frame and normally sustained by a long leaf spring 197 in elevated position determined by the contact of said slide with the tapered point of an adjusting screw 199, best shown in Fig. 5. Obviously by adjusting the screw 199 the limits of throw of the plunger point may be varied.

In the operation of the machine the plunger is so adjusted that it raises a node of goods through the presser-foot opening in appropriate time to be penetrated by the needle's forward thrust, the plunger receding as soon as the needle has penetrated the goods. The feed, of course, makes its effective feeding movement while the needle is out of the goods, and its adjustment is preferably such that the clamp plate is depressed, as heretofore described, during the time that the feed is advancing the work. The stitch is of the well known form shown in Fig. 18.

While I have herein described a specific embodiment of my invention for purposes of a full and operative disclosure thereof it will be understood by those skilled in the art that many changes might be made in structure and arrangement within the spirit of my invention and within the scope of the appended claims.

50 What I claim is:

1. In a sewing machine, stitch forming mechanism comprising a reciprocating needle, a needle-thread take-up, a needle-thread looper having a vibrating part, and means to move the take-up in harmony with the vibrating part of the looper through a part only of the movement of the latter.

2. In a sewing machine the combination of a reciprocating needle, a looper mechanism having a vibrating part, a take-up arm, yielding connections between the take-up arm and the vibrating part of the looper, and a stop for the take-up arm arranged to

prevent the take-up arm following the full course of movement of the looper part. 65

3. In a sewing machine, stitch forming mechanism comprising a reciprocating needle, a main shaft, a needle thread looper mechanism co-operating therewith actuated by said main shaft and co-operating with 70 said needle, and a needle thread take up mechanism mounted for movements distinct from those of said needle and said looper mechanism and operated by said looper mechanism. 75

4. In a sewing machine, stitch-forming mechanism comprising a reciprocating needle, a vertical looper member arranged to work about said needle, a looper bar horizontally disposed and at its active end carrying said looper, a swinging yoke, means to move said yoke to move the looper bar bodily up and down and axially, means to oscillate said looper bar about its own axis, a take-up, a yielding connection between the 85 take-up and the yoke, and a stop for the take-up arranged for preventing the same from following the full course of movement of said yoke. 80

5. In a sewing machine, stitch-forming 90 mechanism comprising a reciprocating needle, a movable part arranged for a relatively long range of movement, a take-up arm, a yielding connection between the take-up arm and said movable part, and a stop for 95 take-up arm arranged to prevent said arm from following the full course of movement of said movable part.

6. In a sewing machine, stitch-forming mechanism comprising a reciprocating needle, a needle thread looper mechanism co-operating therewith, a needle thread take-up lever pivotally supported independently of said looper mechanism, and operative connections between said take-up lever and 100 said looper mechanism to operate said take-up from said looper mechanism. 105

7. In a sewing machine, stitch-forming mechanism comprising a reciprocating needle, a needle thread looper mechanism co-operating therewith having a vibrating part, a take-up lever, a stop restricting the movement of the take up lever in one direction, a second lever resiliently connected to the take-up lever to move the latter away from 110 the stop and to move away from the take-up lever when the latter is stopped in its travel in the opposite direction, and a link connection between the last recited lever and the vibrating part of the looper mechanism. 115 120

In testimony whereof I hereunto set my hand in the presence of two witnesses.

JAMES WHITELAW.
